UNITED STATES PATENT OFFICE.

PETER ISLES, OF SWISSVALE, PENNSYLVANIA.

FURNACE.

Application filed April 2, 1923. Serial No. 629,514.

To all whom it may concern:

Be it known that I, PETER ISLES, a citizen of the United States, and resident of Swissvale, in the county of Allegheny and State of Pennsylvania, have invented certain new and useful improvements in Furnaces, of which the following is a specification.

This invention relates to open-hearth furnaces and more particularly to the framing for the main portion of the furnace, and has for one of its objects the provision of a framing structure for this class of furnaces that will be generally superior to those heretofore used.

Another object is to provide a framing in which the buckstays may be readily replaced without dismantling the furnace.

A further object is to provide a continuous girder support along the entire length of the furnace side wall, which will extend up to the door sills, thus forming a rigid support for this portion of the furnace.

A still further object is to provide novel bracing and anchoring means for the framing structure which will rigidly anchor and tie the several elements together.

The above and other objects will be more fully brought out in the following specifications and illustrated in the accompanying drawings.

In the drawings, Figure 1 is a top plan partly in section of an open hearth furnace embodying this invention.

Figure 2 is a side elevation of the same, partly in section.

Figure 3 is a transverse sectional elevation on the line III—III of Figure 2.

Figure 4 is a transverse sectional elevation on the line IV—IV of Figure 2.

Referring more particularly to the drawings the letter A designates the body of the furnace as a whole, which comprises refractory side walls 2 and 3, end walls 4 and 5, top and bottom walls 6 and 7 and port or "dog" houses 8 and 9.

The body A is of the usual and well known construction and is provided with the usual combined air and gas ports 10 and 11 at the respective ends thereof, which ports communicate at their rear ends with air uptake flues 10^a and 11^a, respectively, and have gas supply conduits 13 entering through their side walls. The side walls of the body A are also provided with the usual charging doorways 12.

The refractory body of the furnace is sup-

ported by a framing of novel construction comprising I-shaped base girders 14 and 15 along each side wall and short end girders 16 which extend along the end walls from the girders 14 and 15 to the dog houses 8 and 9. The girders 14, 15 and 16 are preferably plate girders and extend upwardly along the furnace walls to a point approximately on a line with the bottom of the doorways 12 and form a base for the framing as a whole.

The girders 14, 15 and 16 are each provided with an anchor plate 18 which extends inwardly and is embedded in the bottom wall of the furnace, and anchor brace members 19 are secured to the girders adjacent their upper edges and extend downwardly and are secured to the anchor plates 18 so as to firmly anchor and support the girders.

The girders 14 and 15 are further supported and tied together at their ends by transverse tie beams 23 which extend under the furnace at each end and are secured to the bottom flanges of the girders adjacent their ends.

A plurality of buckstays 20 are spaced around the side and ends walls of the furnace. The buckstays 20 have their lower ends bolted or otherwise secured to the upper flanges of the girders 14, 15 and 16 and have their upper ends tied together by longitudinal beams 21 and transverse beams 22. The transverse beams 22 are secured to the buckstays on opposite sides of the furnace. The buckstays 20 are arranged in groups consisting of two buckstays each, being spaced apart and located adjacent the center of each side wall, thus serving to support the middle portion of the furnace, and a group of four of the buckstays 20 is located adjacent the ends of the side walls 2 and 3 and other groups of four of the buckstays 20 are located adjacent each end of the end walls 4 and 5. The groups of buckstays located adjacent the ends of each side and end wall serve as corner binders.

The buckstays of each of the above groups are secured together by tie plates 24 at points just above the roof of the furnace, and diagonal brace rods 25 have one end secured in the tie plates 24 and extend up and have their other end secured to the transverse tie beams 22. Thus the center of the buckstays are prevented from bulging and the roof thrust is amply taken care of.

The doorways 12 are each provided with

door frames 26 which have their sills supported on the top flange of the side girder 15, thus eliminating the necessity of separate supporting structures for these members.

5 A framing constructed as above described provides a more efficient support for the refractory furnace body than the framing heretofore used, and has the added advantage of providing for the ready replacement of buckstays and corner binders without dismantling the whole or major portion of the furnace.

10 While I have illustrated and described only the preferred embodiment of my invention it will be understood that I do not wish to be limited to the exact construction shown, since various modifications may be made without departing from the scope of my invention as defined in the appended 15 claims.

I claim:

1. In an open-hearth furnace having the usual bottom, side and top walls of refractory material, the side walls being provided 25 with the usual door openings, a metallic supporting framework comprising longitudinally disposed I-beam base girders extending continuously from end to end of said furnace side walls and extending upwardly to a point approximately on a line with the lower face of the door openings, anchor plates secured to the bottom flanges of said girders and extending inwardly and being embedded in the bottom wall of said 30 furnace, transverse tie beams extending under each end of said furnace and secured to the bottom flanges of said girders to prevent spreading thereof, anchor braces secured to said girders adjacent their upper edges and 35 to said anchor plates to further support said girders, a plurality of buckstays spaced along the side walls of said furnace, said buckstays having their lower ends secured to the upper flanges of said girders and extending upwardly an appreciable distance 40 above the top of said furnace, transverse top tie beams secured to the upper ends of said buckstays and a diagonal tie rod secured to each of said buckstays and extending upwardly to the top tie beam to further support said buckstays.

2. In an open-hearth furnace having the usual bottom, side and top walls of refractory material, the side walls being provided 55 with the usual door openings, a metallic supporting framework comprising longitudinally disposed I-beam base girders extending continuously from end to end of said furnace side walls and extending upwardly to a point approximately on a line with the lower face of the door openings, anchor plates secured to the bottom flanges of said girders and extending inwardly and being embedded in the bottom wall of said 60 furnace, transverse tie beams extending 65

under each end of said furnace and secured to the bottom flanges of said girders to prevent spreading thereof, anchor braces secured to said girders adjacent their upper edges and to said anchor plates to further support said girders, a plurality of buckstays spaced along the side walls of said furnace, said buckstays having their lower ends secured to the upper flanges of said girders and extending upwardly an appreciable distance above the top of said furnace, door frames surrounding the doorways in said furnace side walls, said door frames being supported on and secured to the top flanges of said girders, and transverse means for tying the upper ends of the buckstays on the opposite sides of the furnace together.

3. In an open-hearth furnace having the usual bottom, side and top walls of refractory material, the side walls being provided 70 with the usual door openings, a metallic supporting framework comprising longitudinally disposed I-beam base girders extending continuously from end to end of said furnace side walls and extending upwardly to a point approximately on a line with the lower face of the door openings, anchor plates secured to the bottom flanges of said girders and extending inwardly and being embedded in the bottom wall of said furnace, anchor braces secured to said girders adjacent their upper edges and to anchor plates to support and tie said girders in position, a plurality of buckstays spaced along the side walls of said furnace, said 75 buckstays having their lower ends secured to the upper flanges of said girders, and extending upwardly an appreciable distance above the top of said furnace, door frames surrounding the doorways in said furnace 80 side walls, said door frames being supported on and secured to the top flanges of said girders and transverse means for tying the upper ends of the buckstays on the opposite sides of the furnace together.

4. In an open-hearth furnace having the usual bottom, side and top walls of refractory material, the side walls being provided 85 with the usual door openings, a metallic supporting framework comprising longitudinally disposed I-beam base girders extending continuously from end to end of said furnace side walls and extending upwardly to a point approximately on a line with the lower face of the door openings, anchor plates secured to the bottom flanges of said girders and extending inwardly and being embedded in the bottom wall of said furnace, anchor braces secured to said girders adjacent their upper edges and to anchor plates to support and tie said girders in position, a plurality of buckstays spaced along the side walls of said furnace, said 90 buckstays having their lower ends secured to the upper flanges of said girders, and 95

- extending upwardly an appreciable distance above the top of said furnace and transverse means for tying the upper ends of the buckstays on the opposite sides of the furnace 5 together.
5. In an open-hearth furnace having the usual bottom, side and top walls of refractory material, the side walls being provided with the usual door openings, a metallic supporting framework comprising longitudinally disposed I-beam base girders extending continuously from end to end of said furnace side walls and extending upwardly to a point approximately on a line with the 10 lower face of the door openings, anchor plates secured to the bottom flanges of said girders and extending inwardly and being embedded in the bottom wall of said furnace, anchor braces secured to said girders 15 adjacent their upper edges and to anchor plates to support and tie said girders in position, a plurality of buckstays spaced along the side walls of said furnace, said buckstays having their lower ends secured to 20 the upper flanges of said girders, and extending upwardly an appreciable distance above the top of said furnace, door frames surrounding the doorways in said furnace side walls, said door frames being supported 25 on and secured to the top flanges of said girders, transverse top tie beams secured to the upper ends of the buckstays on the opposite sides of the furnace and diagonal tie rods secured to each of said buckstays and 30 extending upwardly to the top tie beam to further support said buckstays and prevent bulging thereof.
6. In an open hearth furnace having the usual bottom, side and top walls of refractory material, the side walls being provided with the usual door openings, a metallic supporting framework comprising longitudinally disposed base girders extending from end to end of said furnace side walls and extending upwardly to a point approximately 35 on a line with the lower face of the door openings, anchor plates secured to said girders and extending inwardly and being embedded in the bottom wall of said furnace, transverse tie beams extending under each end of said furnace and secured to said girders to prevent spreading thereof, anchor braces secured to said girders and to said anchor plates to further support said girders, a plurality of buckstays spaced along 40 the side walls of said furnace, said buckstays having their lower ends secured to said girders and extending upwardly an appreciable distance above the top of said furnace, transverse top tie beams secured to the upper 45 ends of said buckstays and a diagonal tie rod secured to each of said buckstays and extending upwardly to the top tie beam to further support said buckstays.

In testimony whereof I have hereunto set my hand.

PETER ISLES.
